Application filed January 22, 1880. Term of patent 3½ years.

To all whom it may concern:

Be it known that I, JAMES W. TUFTS, of Medford, in the county of Middlesex and State of Massachusetts, have invented and produced
5 a new and original Design for a Holder for Flowers, Matches, &c., of which the following is a full, clear, and exact description, reference being had to the accompanying photograph, making part of this specification.

10 This invention consists in a design for a holder for flowers, matches, &c., to be used as an ornament for tables, mantel-pieces, &c.

15 In the photograph, A represents a canoe, which serves as a holder for flowers, matches, &c. B is a paddle, which extends diagonally across the top of the canoe, to which it is attached.

The canoe A rests upon a pair of upright supports or standards, C C, between which is a curved or arched brace, D, a beautiful and 20 unique design being thus produced.

What I claim as my invention, and desire to secure by Letters Patent, is—

The design for a holder for flowers, matches, &c., consisting of the canoe A, with its supports C C and paddle B, extending diagonally 25 across its top, substantially as herein shown and described.

Witness my hand this 12th day of January, A. D. 1880.
